(57) CLAIM

The ornamental design for a T-shirt, as shown and described.

DESCRIPTION

FIG. 1 is a front view of a T-shirt showing my new design; and,

FIG. 2 is a front view of an alternate embodiment of the design shown in FIG. 1.

The broken lines showing a T-shirt and graphics depict the portion of the article that forms no part of the claimed design.

1 Claim, 1 Drawing Sheet
